US00D624170S

(12) **United States Design Patent**
Myojin et al.

(10) **Patent No.:** US D624,170 S
(45) **Date of Patent:** ** Sep. 21, 2010

(54) **CASING OF CHEMICAL DIFFUSER**

(75) Inventors: **Hiroyasu Myojin**, Tokyo (JP); **Aya Mikami**, Tokyo (JP); **Ryusuke Baba**, Tokyo (JP)

(73) Assignee: **S.T. Corporation**, Tokyo (JP)

(**) Term: **14 Years**

(21) Appl. No.: **29/347,319**

(22) Filed: **Dec. 3, 2009**

(30) **Foreign Application Priority Data**

Jun. 4, 2009 (JP) 2009-012660

(51) **LOC (9) Cl.** **28-99**

(52) **U.S. Cl.** **D23/366**

(58) **Field of Classification Search** D23/355-369;

FOREIGN PATENT DOCUMENTS

JP D-867199 4/1993

(Continued)

Primary Examiner—Sandra Snapp

(74) *Attorney, Agent, or Firm*—Jean C. Edwards, Esq.; Akerman Senterfitt

(57) **CLAIM**

The ornamental design for a casing of chemical diffuser, as shown and described.

DESCRIPTION

FIG. 1 is a perspective view of a casing of chemical diffuser showing our new design;

FIG. 2 is a front view thereof;

FIG. 3 is a rear view thereof;

FIG. 4 is a right side view thereof, the left side view being a mirror image thereof;

FIG. 5 is a top plan view thereof;

FIG. 6 is a bottom plan view thereof; and,

FIG. 7 is reference view showing the condition in use thereof.

The portions of the article in broken lines are shown for illustrative purposes only and form no part of the claimed design.

1 Claim, 7 Drawing Sheets
